Fig. 1

Fig. 2

Fig. 3

FIGURE 1 is a front view in elevation of a lens showing our new design;

FIGURE 2 is a fragmentary view in section taken along the line 2—2 of FIGURE 1;

FIGURE 3 is a fragmentary view in section taken along the line 3—3 of FIGURE 1;

FIGURE 4 is an enlarged view in elevation as seen from the right in FIGURE 1;

FIGURE 5 is a rear view in elevation; and

FIGURE 6 is a fragmentary view in perspective of a section of the lens.

The dominant features of this design reside in the front face portion shown in full lines on the drawing.

This application is a continuation of our earlier filed application, Serial No. D66,243, filed August 8, 1961 and now abandoned.

We claim:

The ornamental design for a lens, as shown and described.
